UNITED STATES PATENT OFFICE.

DAVID ALTHOUSE, OF FARRAGUT, IOWA.

WINDMILL.

SPECIFICATION forming part of Letters Patent No. 243,751, dated July 5, 1881.

Application filed March 17, 1881. (Model.)

To all whom it may concern:

Be it known that I, DAVID ALTHOUSE, of Farragut, in the county of Fremont and State of Iowa, have invented a new and useful Improvement in Windmills, of which the following is a specification.

Figure 1 is a sectional elevation of my improvement. Fig. 2 is a plan view of the same, part of the cover being broken away.

10 Similar letters of reference indicate corresponding parts.

The object of this invention is to cheapen the construction, increase the durability, and facilitate the controlling of windmills.

15 A represents the tower or frame, upon which the wind-wheel is mounted.

To the top of the frame A is attached a platform, B, the middle part of which is cut away, forming a large circular opening, C, through 20 which the wind can escape.

D is the vertical wheel-shaft, the lower end of which revolves in a socket or thrust-bearing, E, attached to the frame A or other suitable support. To the shaft D, just above the

25 platform B, are attached the wings F of the wind-wheel. The wings F are curved transversely or made semi-cylindrical in form, and have their inner upper corners drawn forward and their inner lower corners drawn to the rear-

30 ward to give them a tendency to discharge the wind downward through the opening C. The wings F are strengthened by a top plate, G, attached to their upper edges.

To the platform B, beyond the outer ends of 35 the wings F, are attached posts H, to the upper ends of which is attached the top plate or cover I.

To the center of the cover I is attached a plate, J, through the center of which the shaft 40 D passes, and which forms a bearing for the said shaft. Upon the shaft D, as a pivot, is placed a circular plate, K, the lower side of which is recessed to receive a coiled spring, L. One end of the spring L is attached to the pivoted plate K, and its other end is attached to the stationary bearing-plate J.

To the outer edge of the pivoted plate K are hinged the inner ends of a number of tangential rods, M, to the outer ends of which are attached the upper ends of a number of arms, N. The arms N pass through curved slots O in the

cover I, and are attached to the chutes or shutters P, which are hinged to the posts H. The chutes P are curved upon the arc of a circle, and are made of such a length that the free 55 end of each chute P, when closed, will overlap the hinged end of the adjacent chute P, and thus inclose the wheel F G and prevent it from being operated upon by the wind.

To the plate K is rigidly attached the inner 60 end of a lever, Q, so that the said plate K can be turned to close the chutes P by operating the said lever Q. The lever Q may be held in place by hooks or other catches attached to the cover I. The lever Q can be operated by hand 65 to close the chutes P by a person standing upon the platform B. We prefer, however, to attach a cord to the lever Q, lead the said cord over a pulley pivoted to a post attached to the frame A, and then lead the said cord downward into such a position that it can be readily reached and operated by the attendant. In this case the lower end of the adjusting-cord 70 can be secured to a belaying-cleat, or by other suitable means.

75 The cord, pulley, and post are not shown in the drawings, as there is nothing new in their construction.

The chutes P are held open by the spring L; or the lever Q can be provided with a second 80 pulley, cord, and post upon the opposite side of the said lever Q from the first set, so that the chutes P can be both opened and closed by operating the lever Q.

Motion can be communicated from the shaft 85 D to the machinery to be driven by gear-wheels, pulleys, and belt, or other suitable means.

To the upper end of the shaft D, or to a cross-head attached to the said upper end, are hinged the upper ends of two arms, R, to the lower 90 ends of which are attached balls S.

To the middle parts of the arms R are hinged the upper ends of two bars, T, the lower ends of which are hinged to a circular plate or disk, U. The disk U is secured to the shaft D in 95 such a way as to be carried around by and with the shaft in its revolution, but can slide freely up and down upon the said shaft.

In the edge of the disk U is formed a groove, V, to receive flanges, hooks, or lips W formed 100 upon or attached to the edge of a disk, X, through the center of which the shaft D passes

and revolves, the said disk X being held from revolving by the bent levers Y. The levers Y are pivoted at their angles to supports Z attached to the top or cover I, and the ends of 5 their upper arms are connected with the disk X. The lower arms of the bent levers Y pass through apertures in the rods M', which may be two of the rods M or other rods connected with the plate K tangentially.

10 With this construction, as the speed of the wind-wheel increases, the balls S are thrown outward by centrifugal force, which movement forces the rods M' inward, turning the plate K and closing the chutes P. As the speed of the 15 wind-wheel decreases the balls S drop, allowing the chutes P to be opened by the spring L.

I am aware that windmills have been provided with governors to regulate the opening and closing of the shutters, and that the latter have been closed by weights; but 20

What I claim as new and of my invention is—

1. In a windmill, the combination, with a 25 platform B, having opening C, of a wind-wheel having wings F connected at the top by a plate, G, at the inner ends to a shaft or hub, and unconnected at the bottom and outer ends, as shown and described, whereby the air enters through the outer ends and exhausts at the 30 bottom through opening C, as set forth.

2. The combination, with the central shaft, D, having weighted arms R R, the pivoted bars T, and the grooved disk U V sliding on said shaft, of the disk or plate X, having curved lips W, the bent levers Y, hooking in holes at 35 the outer ends of said plate, and the loop-rods M' M, which connect with shutter-rods working in the slots of cover, as described, whereby the shutters open and close automatically as the wind rises or falls.

3. In a windmill, the combination, with shutter-rods N, working in slots of cover, of the pivoted loop-rods M' M and the disk K, on central shaft D, whereby the shutters may be opened and closed by a spring and hand-lever 40 attached to the disk, as described.

4. In a windmill, the combination, with the wind-wheel shaft D and the plate K, rods M, and chutes P, of the weighted arms R S, the connecting-bars T, the rotating grooved disk U, 45 the sliding flanged disk X, and the bent levers Y, substantially as herein shown and described, whereby the chutes are closed automatically as the speed of the wind-wheel increases, as set forth.

DAVID ALTHOUSE.
